GAME APPARATUS

Howard Amsden, Meadville, Pa.

Application January 13, 1933, Serial No. 651,598

10 Claims. (Cl. 273—94)

This invention relates to game apparatus, and has for one of its objects to provide an apparatus of this character adapted to be used in connection with a billiard table for the purpose of playing a game simulating the game of football.

To attain the foregoing and other objects, the nature of which will appear as the description proceeds, the invention comprehends a game apparatus which will include a miniature football movable over the representation of a football field, and manually operable means through the medium of which the football may be moved to make gains, sustain losses or make scores as may be determined by the skill of the respective players in the game of pocket billiards.

The invention further comprehends a game apparatus of the character stated, wherein the manually operable means for the football will include a drum, a cable secured to the drum and having a run thereof guided for movement longitudinally of the field, an arm secured to such run of the cable and carrying the football, and a disc secured to the drum and providing means by which it may be manually operated to move the football over the field.

The invention further comprehends an apparatus of the character stated which will include means controlling the direction in which the respective players may rotate the disc, such means permitting each player to move the disc only in the direction of his opponent's goal through distances controlled by the billiard balls as they are pocketed.

The invention further comprehends an apparatus of the character stated which will include means adapted to prevent the rotation of the disc beyond a point necessary to move the football to either one of the goals of the field, and means adapted to prevent distortion of the disc, whereby to prevent injury to the football carrying arm and to the disc.

The invention is hereinafter more fully described and claimed, and illustrated in the accompanying drawings, wherein,

Figure 1 is a perspective view of a portion of a room equipped with a billiard table and my improved game apparatus,

Figure 2 is a view partly in front elevation and partly in vertical section of the game apparatus,

Figure 3 is a sectional view taken on the vertical plane indicated by the line 3—3 of Figure 2,

Figure 4 is a sectional view taken on the vertical plane indicated by the line 4—4 of Figure 3,

Figure 5 is a sectional view taken on the hori-

zontal plane indicated by the line 5—5 of Figure 3, and

Figure 6 is a perspective view of one of the thrust take-up devices for the drum actuating disc.

The game apparatus comprises a casing 1 which is of elongated rectangular formation in elevation and which may be made of metal or any other suitable material. The front, bottom, side and top walls 2, 3, 4 and 5 respectively, of the casing 1 may be formed integrally or made separately and secured together in any suitable manner, and the rear wall 6 of the casing may be removably secured by screws 7 to flanges 8 on the bottom, side and top walls.

The casing wall 2 is provided near its upper end with a pictorial illustration of a football field superimposed on a billiard table. The field 9 has indicated thereon field goal zones 9a and 9b. A horizontal slot 10, formed in the casing wall 2, extends centrally of the field 9 from the goal 11 to the goal 12 of the field. A horizontal arm 13 located in the casing 1, and having its front end extending through the slot 10 has a miniature football 14 secured to such end thereof, and is movable lengthwise of the slot to carry the football over the field 9.

The arm 13 is supported and operated by means preferably comprising a horizontal drum 15, direction pulleys 16, and a cable 17 to which the arm is secured and which passes about the drum and pulleys and is secured to the drum. The drum 15, the periphery of which is equal in extent to the length of the slot 10 is supported by a shaft 18 for rotation about a horizontal axis located below the slot. The drum 15 is fixed to the shaft 18 and the shaft is journaled in bearings 19 carried by the casing walls 2 and 6. The pulleys 16 are rotatably mounted in the casing 1 on shafts 20 which are carried by brackets 21 fixed to the casing wall 2. The pulleys 16, which are located slightly beyond the ends of the slot 10 have the top portions of their peripheries arranged in alignment with the horizontal center of the slot, and the cable 17 is under tension, to support the horizontal run of the cable parallel to such center of the slot. The rear end of the arm 13 is formed to provide a split eye 22 which receives the horizontal run of the cable 17 and which, through the medium of a screw 23, is firmly clamped to the cable. The ends of the cable 17 are coiled about the drum 15, and are secured to the drum by a screw 24.

The periphery of the drum 15 is equal in extent to the length of the slot 10 in order to effect by 110

one complete rotation of the drum the movement of the ball 14 throughout the entire length of the field. The horizontal run of the cable 17 is supported in parallel relation to the longitudinal center of the slot 10, and the width of the slot is greater than the thickness of the arm, to insure the free movement of the arm from end to end of the slot.

Means through the medium of which the drum 10 may be manually rotated to effect the movement of the football 14 over the field 9, preferably comprises a vertical disc 25 secured to the front end of the drum 15 and arranged in close parallel relation to the front casing wall 2. The disc 15 25 is larger diametrically than the drum 15 and is concentrically related to the drum. The disc 25 is provided near its periphery with an opening 26 for each "yard" of the field 9. An instrument, not shown, which may be similar in formation 20 to a stylus, is engaged with a selected one of the annular series of openings 26 to operate the disc 25 to effect the movement of the football 14 over the field 9. To permit of access to the openings 26, the casing wall 2 is provided at opposite sides 25 of the axis of the disc 25 with arcuate slots 27 and 28 with each of which sixteen of the openings 26 register. All but the lowest of the openings 26 registering with the slots 27 and 28, are numbered from 1 to 15, the numbers being on the front side 30 of the casing wall 2 close to the slots, as shown at 27a and 28a.

The drum 15 and disc 25 are of such relative proportions, the openings 26 are so relatively spaced, and the respective openings registering 35 with the slots 27 and 28 are arranged in such spaced relation to the lower ends of the slots, that when the disc is moved to carry one of the openings from its normal position to the lower end 40 of its slot, the football will be moved over the field for a distance corresponding to the distance in "yards" indicated by its number. As for instance, if the instrument is engaged in that opening 26 registering with slot 27 opposite the number 8, and if the instrument is moved to the lower 45 end of the slot, the football 14 will be moved over the field 9 for a distance corresponding to eight yards on a regulation field.

The game is started with the ball on the 50 yard line. The player defending goal 11 operates 50 the disc 25 by engaging the instrument in those openings registering with the slot 28, and the player defending goal 12 operates the disc by 55 engaging the instrument in those openings registering with the slot 27. As the slots 27 and 28 are arranged at opposite sides of the axis of the disc 25, the disc will be moved in one direction when the instrument is engaged with an opening registering with the slot 27, and it will 60 be moved in the opposite direction when the instrument is engaged with an opening registering with the slot 28, with the result that the operation of the disc by one player will move the ball 14 in the direction of his opponent's goal.

The thrust on the edge of the disc 25 resulting 65 from the operation thereof, is taken up by shoes 29 made of felt or other suitable material and carried by brackets 30 secured to the casing walls 4. The shoes 29 contact with the rear side of the disc 25 near the edge thereof, and they 70 are, together with the brackets 30, as long as the slots 27 and 28. The shoes 29 also hold the disc 25 against accidental rotation.

The disc 25 is held against movement through 75 more than 360 degrees in opposite directions by means comprising a stop block 31 fixed to the

rear side of the disc, and a horizontally arranged stop lever 32 connected to a bracket plate 33 fixed to the rear casing wall 6 near the lower edge of the disc. The stop lever 32 is pivoted as at 34, to the bracket plate 33 for limited movement by the stop block 31 from one side to the other of a vertical line intersecting the axis 18 of the disc 25 and this movement is provided for in order to compensate for the thickness of the stop 31. The movement of the stop lever 32 is limited in each direction by angularly related extensions 35 and 36 which are carried by the pivoted end of the lever 32, and one of which contacts with the bracket plate 33 on the movement of the disc 25 through 360 degrees. When the football 14 is on the 50 yard line, the stop block 31 is directly above the stop lever 32, and when the football is at one of the goals 11-12, the stop block is in contact with the stop lever, and one of the shoulders 35-36 of the latter is in contact with the bracket plate 33.

It will thus be seen that the stop mechanism prevents the disc 25 from being moved farther than is necessary to make a goal. The purpose of limiting the movement of the disc 25 is to prevent the ball carrying arm 13 from being moved, and thus injured, after contacting with an end wall of the slot 10.

The apparatus comprises means adapted to indicate or register, independently of the field 9 and football 14, the distance of the football from each of the goals 11 and 12. This means preferably comprises yardage indicating numbers arranged in outer and inner annular series 37 and 37a, on the front side of the disc 25, together with a window 37b in the casing wall 2 and before which the numbers of each series successively appear as the disc is turned to move the football 14 over the field 9. The numbers of each of the series 37-37a range from 1 to 99. The numbers of the outer series 37 increase in value clockwise of the disc 25, and the numbers of the inner series 37a increase in value counterclockwise of the disc. When the disc 25 is turned clockwise to move the football 14 in the direction of the goal 12, the numbers of the outer series 37 successively appear in reverse order before the window 37b, and the numbers of the inner series 37a successively appear in regular order before the window. When the disc 25 is turned counter-clockwise to move the football 14 in the direction of the goal 11, the numbers of the inner series 37a successively appear in reverse order, before the window 37b, and the numbers of the outer series 37 successively appear in regular order before the window.

The number of the outer series 37 appearing before the window 37b after each operation of the disc 25, indicates the distance of the football 14 from the goal 12 and the number of the inner series 37a appearing before the window 37b after each operation of the disc, indicates the distance of the football from the goal 11. As for instance, assuming that the football 14 is within one yard of the goal 12, number 1 of the outer series 37 and number 99 of the inner series 37a will appear before the window 37b, telling the player, at a glance, that the football must travel 99 yards to reach the goal 11 and 1 yard to reach the goal 12. Assuming that the stop block 31 on the disc 25 is now just contacting with the stop lever 32, and the final "yard" is given the player, the stop block will, as the result of the next operation of the disc, move the stop lever in such manner that the shoulder 35-36

will make solid contact with the plate 33 and prevent further operation of the disc in clockwise direction. The football 14 will now be at the end of the slot 10 beneath goal 12, and the "Goal", borne by the disc 25 between highest and lowest numbers of the series 37 and 37a, will be before the window 37b, indicating that a goal has been made. Further operation of the disc 25 is only possible in counter-clockwise direction. The operation of the disc 25 in this direction results in the movement of the football 14 in the direction of the goal 11. When this goal has been made the word "Goal" on the disc 25 will again appear before the window 37b. Arrows 38 and 39 of which the former points in the direction of the goal 11 and the latter in the direction of the goal 12, identify the respective numbers appearing before the window 37b with their respective goals.

Score sheets 40 are supported between the slots 27 and 28 by a member 41 which embraces the upper ends of the sheets and which is secured, as at 41a to the casing wall 2. The score sheets 40 are provided with arrows 40a, each of which points to the slots through which each player operates the disc 25, and the direction in which the football 14 moves over the field 9 as the result of the operation of the disc. The arrows are used for the purpose of indicating the respective columns for the scores of the respective players.

The respective numbers of each of the series 27a and 28a represent the respective object balls 42 used in playing the game of pocket billiards, and each of these numbers is similar in color to the object ball it represents to permit it to be readily identified when the object ball it represents is pocketed and entitles the player to move the football 14 over the field 9 for a distance corresponding in "yards" to the number of the object ball pocketed. If, for instance, the object ball 9 is pocketed the player engages the instrument in that opening of the disc 25 opposite number 9 on casing wall 2, and moves the instrument downwardly until it contacts with the bottom wall of the slot with which such opening registers. The resulting movement of the disc 25 moves the football 14 over the field 9 for a distance corresponding to nine "yards" in a regulation field.

Preparatory to playing the game, which I call "billiard football", the football 14 is moved to the 50 yard line of the field 9, and the object balls 42 are racked on the billiard table 43 in the usual manner. The game is played with a cue 44 and cue ball 45. In accordance with the wishes of the players, the play of the game may be either call-shot or "scratch" style of play. In call-shot all object balls must be called. In "scratch" style of play, any object ball may be shot and they need not be called. For each object ball pocketed by him, with the exception of the 1-ball, 3-ball, and 13-ball, a player moves the football over the field, in the direction of the opponent's goal, the number of "yards" indicated by the number of the pocketed ball. The 1-ball may be played as a "forward-pass", and when so played and pocketed, entitles a player to advance the football twenty "yards". This ball may be also played as a "punt", and when so played and pocketed entitles a player to advance the football forty "yards". The 3-ball when pocketed as such entitles a player to a "field goal", and when the goal is made a player scores three points. The pocketing of the 13-ball constitutes a "fumble",

and a player making a "fumble" sustains a thirteen "yard" loss.

All objects balls pocketed, intentionally or otherwise, are left off the table until a player has missed an object ball, played "safe", "fumbled", punted, or the cue-ball has left the table or entered a pocket. After the score made, if any, has been credited to a player on the score sheet, the balls that were pocketed by the player are spotted in rotation (lowest number first) on the spot at the foot of the table.

If there are more balls than the space between the spot and rail will hold, the remaining balls are arranged from the spot towards the center of the table in their natural sequence. After the balls have been spotted, the other player shoots, and the game ends when the respective players have shot eight frames alternately.

Should a player make sufficient "yardage" to put the football over his opponent's goal, he would make a "touchdown" and score six points. One point additional is scored if the next shot after the touchdown is successful. If the point is made, the player continues to shoot, running the football back from the 50 yard line. This shot cannot be made straight in but must be either a bank, billiard or combination shot, and it must be called in either call-shot or "scratch" style of play. If an object ball is not in a favorable position for either of these shots, a player may waive this extra point and play the shot safe. He must, however, try for this extra point or play the shot safe.

If a player has but 20 to 30 "yards" to go to make a touchdown, and the 3-ball occupies a favorable position on the table, he may call this ball a "field goal" ball, and should he pocket this ball he would make a field goal and score three points. In either call-shot or "scratch" style of play, the player must state before the shot which play he intends to make.

A penalty is imposed, in favor of his opponent, in the event that a player's cue-ball goes off the table, goes into a pocket, or does not hit an object ball. The penalty for the first offense is 5 "yards", for the second offense 10 "yards", and for the third and each succeeding offense 15 "yards". Should a penalty result in placing the football over the goal the player is defending, two points are scored for the opponent. It may be to a player's advantage to deliberately penalize himself, giving his opponent two points, if the score is close and the object balls are in such a position as to present difficult shots, for the reason that with the football so near the goal, the player may be able to make six points and possibly more on his next shot, whereas two points are all that he could make unless he runs the "football" back from the 50 "yard" line. A 15 "yard" penalty is imposed in case a try for a "field goal" is unsuccessful.

In the event that the object balls are in such position as to present difficult shots, a player may call a "punt" shot instead of the usual safe shot. If this shot is made, the football is advanced twice the number of "yards" indicated by the object ball pocketed, and at this point his opponent receives the football. In "scratch" style of play, the player may call a "punt" after the shot has been made. The 1-ball made as a "punt" advances the football forty yards. The player must watch that the "punt" does not carry the football over the goal, for the reason that should this occur the football would have to be

brought back to the player's 20 yard line before play could be resumed.

A player loses the football with a 13 "yard" loss whenever the 13-ball enters a pocket. Any other object balls that may enter a pocket with the 13-ball are not counted. A touchdown is scored for a player's opponent in the event that fumble penalty places the football over the goal.

From the foregoing description, taken in connection with the accompanying drawings, it will be seen that the game includes substantially all the gains, losses, penalties, plays, scores and the like obtained in the game of football as actually played and that the result of the game depends on the skill of the respective players in the game of pocket billiards, and that the game adds to the game of billiards the interest and enthusiasm of the game of football.

Having thus described the invention, what is claimed is:

1. A game apparatus comprising a member bearing on the front side thereof the representation of a football field, said member having a slot extending longitudinally of the field, an arm extending through the slot, a miniature football carried by the front end of said arm, means located rearwardly of said member and having the arm connected thereto, said means being operable to move the arm lengthwise of the slot, and a disc rotatably mounted at the rear side of said member and connected to said means and constituting an operating member therefor, the disc being provided with a series of openings, and said member being provided at opposite sides of the axis of the disc with slots through which some of the openings may be engaged to effect the operation of the disc.

2. A game apparatus comprising a member bearing on the front side thereof the representation of a football field and provided with a slot extending longitudinally of the field, an arm extending through the slot, a miniature football secured to the front end of the arm, a drum and guide pulleys at the rear side of said member, a cable passing about the pulleys and secured to the drum for operation thereby, the pulleys supporting a part of the cable for movement lengthwise of the slot, the arm having its rear end secured to said part of the cable, and a disc secured to the drum and movable in opposite directions to actuate the drum, the disc being provided with a series of openings near its edge, and said member being provided at opposite sides of the axis of the disc with slots through which some of the openings may be engaged to effect the operation of the disc.

3. A game apparatus comprising a member bearing on the front side thereof the representation of a football field and provided with a slot extending longitudinally of the field, an arm extending through the slot, a miniature football secured to the front end of the arm, a drum and guide pulleys at the rear side of said member, a cable passing about the pulleys and secured to the drum for operation thereby, the pulleys supporting a part of the cable for movement lengthwise of the slot, the arm having its rear end secured to said part of the cable, a disc secured to the drum and movable in opposite directions to actuate the drum, the disc being provided with a series of openings near its edge, said member being provided at opposite sides of the axis of the disc with slots through which some of the openings may be engaged to effect the operation

of the disc, and means for limiting the operation of the disc in each direction.

4. A game apparatus comprising a member bearing on the front side thereof the representation of a football field and provided with a slot extending longitudinally of the field, an arm extending through the slot, a miniature football secured to the front end of the arm, a drum and guide pulleys at the rear side of said member, a cable passing about the pulleys and secured to the drum for operation thereby, the pulleys supporting a part of the cable for movement lengthwise of the slot, the arm having its rear end secured to said part of the cable, a disc secured to the drum and movable in opposite directions to actuate the drum, the disc being provided with a series of openings near its edge, said member being provided at opposite sides of the axis of the disc with slots through which some of the openings may be engaged to effect the operation of the disc, and means bearing against the disc near the edge thereof to take up the thrust on the disc when an opening is engaged and the disc is being operated.

5. A game apparatus comprising a member bearing the representation of a football field and provided with a slot extending longitudinally of the field, an arm extending through the slot, a miniature football secured to the arm, a drum and guide pulleys at the rear side of said member, a cable passing about the pulleys and secured to the drum for operation thereby, the pulleys supporting a part of the cable for movement lengthwise of the slot, the arm being secured to said part of the cable, a disc secured to the drum and movable in opposite directions to actuate the drum, the disc being provided with a series of openings, said member being provided at opposite sides of the axis of the disc with slots through which some of the openings may be engaged to effect the operation of the disc, and means bearing against the disc near the edge thereof to take up the thrust on the disc when an opening is engaged and the disc is being operated.

6. A game apparatus comprising a member bearing on the front side thereof the representation of a football field and provided with a slot extending longitudinally of the field, an arm ex-

tending through the slot, a miniature football secured to the front end of the arm, a drum and guide pulleys at the rear side of said member, a cable passing about the pulleys and secured to the drum for operation thereby, the pulleys supporting a part of the cable for movement lengthwise of the slot, the arm having its rear end secured to said part of the cable, a disc secured to the drum and movable in opposite directions to actuate the drum, the disc being provided with a series of openings near its edge, said member being provided at opposite sides of the axis of the disc with slots through which some of the openings may be engaged to effect the operation of the disc, a stop block secured to the disc, and a stop lever mounted for limited rocking movement in the path of the stop block.

7. A game apparatus comprising a member bearing on the front side thereof the representation of a football field and provided with a slot extending longitudinally of the field, an arm extending through the slot, a miniature football secured to the front end of the arm, a drum and guide pulleys at the rear side of said member, a cable passing about the pulleys and secured to the

- drum for operation thereby, the pulleys supporting a part of the cable for movement lengthwise of the slot, the arm having its rear end secured to said part of the cable, a disc secured to the drum and movable in opposite directions to actuate the drum, the disc being provided with a series of openings near its edge, said member being provided at opposite sides of the axis of the disc with slots through which some of the openings may be engaged to effect the operation of the disc, a stop block secured to the disc, a stop lever mounted for limited rocking movement in the path of the stop block, and thrust take-up members contacting with the disc near the edge thereof adjacent the slots through which the disc openings are accessible.
8. In a game apparatus for operation by an actuator, a member bearing the representation of a football field and having a slot, a miniature football movable over the field and having an arm movable in said slot, a rotatable disc mounted at one side of said member and having connection with said arm for moving the same in said slot, said disc having circularly extending means for engagement by an actuator, said member being formed at opposite sides of the axis of said disc with separate arcuate slots exposing oppositely located portions of said circularly extending means and having ends limiting movement of an actuator.
9. In a game apparatus for operation by an actuator, a member bearing the representation of a football field and having a slot, a miniature football movable over the field and having an arm movable in said slot, a rotatable disc mounted at one side of said member and having connection with said arm for moving the same in said slot, said disc having circularly extending means for engagement by an actuator, said member being formed at opposite sides of the axis of said disc with separate arcuate slots exposing oppositely located portions of said circularly extending means and having ends limiting movement of an actuator.
- 35 10. In a game apparatus for operation by an actuator, a member bearing the representation of a football field and having a slot, a miniature football movable over the field and having an arm movable in said slot, a rotatable disc mounted at one side of said member and having connection with said arm for moving the same in said slot, said disc having circularly extending means for engagement by an actuator, said member being formed at opposite sides of the axis of said disc with separate arcuate slots exposing oppositely located portions of said circularly extending means and having ends limiting movement of an actuator, and stop members of arcuate form for engagement by the peripheral portions of said discs and being located in line with said slots.
